Primary Examiner—A. Hugo Word*Assistant Examiner*—Celia A. Murphy*Attorney, Agent, or Firm*—Mason, Fenwick & Lawrence**[57] CLAIM**

The ornamental design for a tool box or similar article, as shown and described.

DESCRIPTION

FIG. 1 is a top perspective view of a tool box or similar article showing my new design;

FIG. 2 is a bottom perspective view thereof;

FIG. 3 is a top perspective view thereof, the handles shown in an upright position;

FIG. 4 is a top perspective view thereof, the lids shown open;

FIG. 5 is a top perspective view of an alternate embodiment of the design shown in FIG. 1;

FIG. 6 is a bottom perspective view of FIG. 5;

FIG. 7 is a top perspective view of FIG. 5, the handles shown upright;

FIG. 8 is a top perspective view of FIG. 5, the lid shown open, and the drawers shown extended;

FIG. 9 is an enlarged top plan view of FIG. 4;

FIG. 10 is an enlarged bottom plan view of FIG. 8; and,

FIG. 11 is a left side elevational view of FIG. 10.
